UNITED STATES PATENT OFFICE.

FRANK C. KLEMA, OF WILSON, KANSAS.

CARBURETER.

1,210,329.

Specification of Letters Patent. Patented Dec. 26, 1916.

Application filed June 22, 1915. Serial No. 35,892.

To all whom it may concern:

Be it known that I, FRANK C. KLEMA, a citizen of the United States, residing at Wilson, in the county of Ellsworth and State of Kansas, have invented new and useful Improvements in Carbureters, of which the following is a specification.

This invention relates to carbureters and particularly to air admission valves for carbureters whereby the proper amount of air is automatically admitted to the carbureter at high and low speed and at all intermediate speeds, proportionate to the demands of the engine and the supply of gasoline drawn from the carbureter by the suction of the piston or pistons of the engine.

With the above and other objects in view, the invention consists in the novel construction, combination and arrangement of parts, as herein described, illustrated and claimed.

In the accompanying drawings:—Figure 1 is a vertical section through a portion of a carbureter embodying the present invention, showing the air controlling mechanism and the throttle valve. Fig. 2 is a section taken at right angles to Fig. 1 showing the means for adjusting the blades or sections of the damper. Fig. 3 is a horizontal section taken just under the top wall of the carbureter.

Referring to the drawings 1 designates the body of a carbureter of the conventional type, the same being provided with a relatively enlarged air chamber 2, 3 designating the outlet nozzle of the carbureter in which is located the usual butter fly or throttle valve 4 controlled in the usual way for supplying more or less mixture to the engine in accordance with the speed thereof.

In carrying out the present invention, an air inlet opening 5 is formed in the bottom of the carbureter and is partially or wholly closed by means of a valve 6. It is preferred, however, to make the valve slightly less in diameter than the opening 5 so that sufficient air will be admitted to enable the engine to continue running at low speed. The valve 6 is guided by a stem 7 which is received in an adjustable stop or bearing 8 threaded through the top of the carbureter as shown at 9 and held when adjusted by means of a jam nut 10. A valve closing spring 11 of the coiled expansion type is interposed between the valve and the stop 8 so that by adjusting said stop, the spring 11 may be placed under greater or less ten-

sion in adjusting the air valve to suit any particular engine.

12 designates a strap extending under the opening 5 above referred to and diametrically across the same, the valve 6 being formed with a pendent extension or hub-like portion 13 which comes in contact with the strap 12 to limit the downward movement of said valve and hold the same with- in the opening 5.

Encircling the opening 5 and extending upwardly therefrom is a damper comprising a circular series of sections 14. These sections are hinged along their bottom edges as shown at 15 to the bottom wall of the carbureter and the upper edges thereof are connected by links 16 to an annular yoke 17. Stems 18 extend upwardly from said yoke through holes 19 in the top of the carbureter where they are threaded to receive nuts 20. Springs 21 encircle said stems between the yoke and the top of the carbureter and in conjunction with the nuts last referred to, enable said annular yoke to be moved upwardly or downwardly for the purpose of moving the upper extremities of the damper blades inwardly or outwardly. It will be observed that the blades 14 are so arranged that they may be positioned edge to edge thus constituting in effect a continuation of the opening 5 having the same cross sectional area as said opening. In such position, the opening of the valve 6 by the movement thereof along its guiding stem 7 will not increase the opening around the same for the reason that the clearance between the edge of the valve 6 and the wall of the cylindrical tube formed by the blades 14 will be the same as the clearance between the edge of the valve and the wall of the opening 5. If, however, the blades 14 are arranged at an angle to the axis of the valve guide, then increased opening of the valve will necessarily result in an increase in the amount of clearance between the valve and the inner surfaces of the blades 14 and will thus result in an increase in the inflow of air. It will thus be seen that it is not because of the V-shaped spaces between the blades 14 that more air is admitted but because of the inclination of said blades which allows for a greater clearance between the valve and said blades, the V-shaped spaces being merely incident to the variation in the position of said blades. The blades or sections of the damper are preferably adjusted

while the engine is running at high speed so that sufficient air is insured to provide for the highest speed desirable. After the proper adjustment has been obtained, the 5 blades or sections of the damper are held in the position where they are left, the movement of the blades being utilized only for the purpose of adjusting the air supply to different engines.

10. From the foregoing description, the operation of the invention will now be understood. As the throttle valve 4 is opened for the purpose of speeding up the engine, more gasolene is drawn from the carbureter and 15 on account of the increased suction, the air valve 6 is lifted in proportion to the amount of gasolene being drawn from the carbureter thereby automatically increasing the air supply in proportion to the increased consumption of gasolene. Therefore, a proper mixture of air and gasolene is obtained at all speeds of the engine, doing away with the high, low and intermediate speed adjustments now commonly employed in carbureters as at present manufactured.

What I claim is:—

1. The combination with a carbureter, of an air inlet valve adapted to open in proportion to the suction thereon, and a damper 30 surrounding the air inlet zone and embodying a plurality of blades having their adjacent edges divergent to leave V-shaped air spaces.

2. The combination with a carbureter, of an air inlet valve adapted to open in proportion to the suction thereon, and a damper 35 surrounding the air inlet zone and embodying a plurality of blades having their adjacent edges divergent to leave V-shaped air spaces, said blades being simultaneously adjustable toward and away from the path of movement of the valve to vary the area of the spaces between the edges of the blades.

3. The combination with a carbureter, of an air inlet valve adapted to open in proportion to the suction thereon, a damper 45 surrounding the air inlet zone and embodying a circular series of blades attached at one end to the interior of the carbureter, and means for adjusting the opposite ends of 50 the blades toward and away from each other and the path of movement of said valves.

4. The combination with a carbureter, of an air inlet valve adapted to open in proportion to the suction thereon, a spring for 55 closing said valve, means for adjusting the tension of said spring, and a damper surrounding the air inlet zone and embodying a plurality of blades having their adjacent edges divergent to leave V-shaped air spaces. 60

In testimony whereof I affix my signature in presence of two witnesses.

FRANK C. KLEMA.
